(57) CLAIM

The ornamental design for a martial arts hand guard, as shown and described.

DESCRIPTION

FIG. 1 is a top view of a martial arts hand guard showing our new design;

FIG. 2 is a bottom view thereof;

FIG. 3 is a front view thereof;

FIG. 4 is a rear view thereof;

FIG. 5 is a side view thereof; the opposite side being a mirror image thereof;

FIG. 6 is a front perspective view thereof; and,

FIG. 7 is a perspective view of the martial arts hand guard of FIG. 1, depicting the martial arts hand guard being used to hold a board.

The broken lines depicting the second guard and the board are provided for purposes of environment and form no part of the claimed design.
